UNITED STATES PATENT OFFICE.

WILLIAM C. HOMAN, OF MERIDEN, CONNECTICUT, ASSIGNOR TO LINDSAY LIGHT COMPANY, OF CHICAGO, ILLINOIS, A CORPORATION OF ILLINOIS.

GLOBE SUPPORT.

Application filed July 26, 1923. Serial No. 653,866.

To all whom it may concern:

Be it known that I, WILLIAM C. HOMAN, a citizen of the United States of America, and a resident of Meriden, in the county of 5 New Haven and State of Connecticut, have invented certain new and useful Improvements in Globe Supports, of which the following is a specification.

The present invention relates to globe 10 supports and method of making the same, and more particularly to a type of circular globe support suitable for holding globes for electric or gas fixtures.

These globe supports should be light in 15 weight, easy to assemble and to manipulate, and of comparatively inexpensive construction. In order to secure a light weight structure, these supports have heretofore been made out of blanks of sheet metal by 20 suitably punching or stamping the same. An example of such a holder is shown in Van Gelderen Patent No. 1,071,537, granted August 26, 1913. In making up the circular 25 and the arcuate parts of this type of globe support out of sheet metal, it is impossible to avoid a large percentage of waste material.

An object of the present invention is to make the movable parts of the globe holder 30 without appreciable waste of material, thereby economizing the same.

A further object of the present invention is to make parts of the frame out of wire, preferably steel, pressed to shape.

Another object of the present invention 35 is to provide a compact globe holder which may be readily assembled out of light weight but strong parts.

The accompanying drawings show for 40 purposes of illustrating the invention, one of the many possible forms in which the present invention may be embodied. In these drawings:

Fig. 1 is a vertical section showing the shade holder mounted in a canopy, the 45 globe being released; and

Fig. 2 is a horizontal sectional view on the line 2—2 of Fig. 1, the parts being in position to clamp the globe in place.

In Fig. 1 a canopy 10, which may be of any 50 suitable shape and size for the particular globe which is to be used, is provided with a short, cylindrical lower skirt portion 11 underneath an annular shoulder 12, and with a bead 13. The globe support, which 55 forms the subject matter of the present in-

vention, is mounted inside the cylindrical portion 11 of the canopy. An annular ring or casing 14, which may be made of a sheet metal stamping, has an inwardly turned lower flange 15, and is of the proper size to fit loosely inside of the cylindrical portion 11.

The flange 15 is provided with a plurality, in the present case three, holes 16 for rivets 17. These rivets provide pivotal mountings 65 for three globe clamping members 18. Directly above the globe clamping members there is shown an annular shaped actuating ring 19 which has a plurality of holes or slots 20 to receive the upwardly bent end 21 70 of the globe clamping members 18. The ring 19 is provided with a block 22 which may be riveted to it as indicated and this block is provided with a threaded stud 23 which passes outwardly through a slot 24 75 in the side wall of the ring 14 and through a slot 25 in the cylindrical portion 11 of the canopy.

It will be noted that the actuating ring 80 and arcuate clamping members are of such shape that, if made out of sheet metal by punching, there would be considerable waste. According to the present invention, however, these members are made out of flattened steel wire. The round wire is 85 passed through suitable dies or rolls to flatten it to the desired thickness and width, and the flattened wire is then wound into a helical coil of the proper diameter after which the wire may be tempered or be 90 treated as desired so that it will remain permanently in shape. The coiled wire is then cut to provide pieces of the proper size. In the device as shown in the drawings, one complete coil of the helix is severed to provide the actuating ring 19 and three semi-circular pieces of the flattened wire are severed to provide the globe clamping members. 95

Each of the globe clamping members is 100 punched to provide a hole 26 for the rivet 17 while the other end 27 of the member is formed to the shape shown by bending up the end 21 and cutting away the slight amount of excess material along the line 28. The ends 29 and 30 of the actuating ring 19 are brought together and fastened by the rivets which hold the block 22 in place. These parts may be assembled in the ring 14 by first riveting the clamping members 110

18 in place, then bringing the ring 19 down underneath the prong 31 which has been struck inwardly from the ring 14. The ring 19 and the ends of the clamping members 18 are suitably disposed so that the upturned ends 21 may enter the slots 20 and the stud 23 is passed down through a vertical slot 32 which communicates with the slot 24. To assemble this device in the canopy, the stud 23 is pushed out through the slot 25 and the ring 14 and the parts carried thereby are moved into the position of Fig. 1. A thumb-screw or wing-nut 33 is threaded on to the stud 23 and a screw 34 is passed through the walls 11 and 14 to secure the parts in place.

To clamp a globe 35 or other device in place it is raised to the position as indicated by dotted lines in Fig. 1 whereupon the actuating ring is moved toward the position indicated in Fig. 2, the projecting stud being available to move the ring. The ring is guided by the stud and the prong 31, and by its movement carries the movable ends of the globe clamping members a short distance, swinging these members on their pivots and bringing them into the position of Fig. 2. The thumb-screw or wing-nut may be tightened against the canopy thereby fixing the parts in position.

The globe retainer which has been described is a very light weight structure and utilizes material efficiently and without waste. On account of economizing material and being very easy to assemble, it has been found that this type of globe support has considerable advantage over those made out of sheet metal stampings.

While the structure disclosed has three clamping members it is of course obvious

that a different number of members could be used without departing from the spirit of the invention. It is also obvious that the invention is not limited to steel wire as brass or other wire would be suitable.

45

I claim:

1. A shade holder comprising an outer casing, having an inturned flange, an annulus of flat wire, spaced from the flange, and a plurality of semi-circular globe clamping members of flat wire, each member having one end pivoted to the flange and the other end pivoted to the annulus. 50

2. A shade holder, comprising an internally flanged sheet metal ring, the flange having a plurality of regularly spaced apertures, an actuating ring of flattened wire spaced above the flange, the ring having a plurality of regularly spaced apertures, and a plurality of semi-circular flattened wire globe clamping members intermediate the flange and actuating ring, and pivoted in the apertures. 55

3. A shade holder, comprising an internally flanged sheet metal ring, the flange having a plurality of regularly spaced apertures, an actuating ring of flattened wire spaced above the flange, the ring having a plurality of regularly spaced apertures, a plurality of semi-circular flattened wire globe clamping members intermediate the flange and actuating flange ring, and pivoted in the apertures, the side of the ring having a slot, a stud passing through the slot, and a clamping nut on the stud. 60

Signed at Meriden in the county of New Haven and State of Connecticut this 23rd day of July 1923.
